R. H. GORE

EXERCISE. BED

Filed May 2, 1925

UNITED STATES PATENT OFFICE.

ROBERT HAYES GORE, OF CHICAGO, ILLINOIS.

EXERCISE BED.

Application filed May 2, 1925. Serial No. 27,606.

To all whom it may concern:

Be it known that I, ROBERT H. GORE, a citizen of the United States, residing at Chicago, in the county of Cook and State of Illinois, have invented certain new and useful Improvements in Exercise Beds, of which the following is a specification, reference being had to the accompanying drawings.

10 This invention relates to beds, and particularly to metallic beds, and the general object of the invention is to provide a bed so constructed that exercises may be taken therein while lying upon the bed.

15 A further object is to provide a bed of this character having coiled contractile springs arranged in the bottom of the bed, pulleys arranged in certain posts of the head board and foot of the bed, and flexible cords 20 attached to the springs and extending over said pulleys and by which the arms and legs of the person lying in the bed may be readily exercised.

25 A still further object is to provide a device of this character having posts forming part of the head and foot board of the bed, the cords being conducted through said posts and out of openings therein, one pair of cords being provided with means whereby 30 the feet may be connected to the cords and the other being provided with handles, these tubular posts being provided with housings whereby the handles and foot-connecting parts are housed and concealed.

35 My invention is illustrated in the accompanying drawing, wherein:—

Figure 1 is a vertical sectional view of an exercising bed constructed in accordance with my invention, showing in dotted lines

40 the method of using the bed;

Figure 2 is a top plan view of the structure shown in Figure 1;

Figure 3 is an end view looking toward the foot board.

45 Referring to this drawing, it will be seen that I have illustrated an ordinary bed comprising the usual corner posts 10, the head board and foot board 11 and 12 respectively, and the longitudinal side rails 13. The head board and foot board are constructed as usual of transverse tubular elements 14 and vertical tubular elements 15.

50 Forming part of the head board and foot board are two pairs of relatively larger tubular elements 16, there being a pair at the foot board and a pair at the head board,

and these tubular elements being connected to the frame of the head board in any suitable manner as, for instance, by the collars 17 with which the rails 14 engage. These pairs of tubular elements 16 are disposed in alignment with each other and the lower end of each tubular element is bent toward the other end of the bed, as at 18, at a point beneath the bed bottom, or in other words 60 beneath the side rails 13 upon which the bed bottom is supported. The curved ends 18 of the tubular elements are connected by means of a pair of longitudinally extending tubes 19, each tube having at its middle a plug 20 or equivalent member which are shown as held in place by means of a rivet 21, and connected to each plug on opposite sides thereof are the coiled springs 22 and 23. The coiled springs 22 have engaged 70 with their forward ends the flexible cords 24 and these pass around the curved ends 18, then pass upward and over rollers 25 or rounded beads at the openings 26. Surrounding these openings 26 are the housings 27 and these cords 24 are connected to foot pieces 28 having the form of sandals and held in engagement with the foot by crossed straps. Any equivalent devices may be used 80 for this purpose, however.

85 The housings are normally covered by means of a lid 27 which is hinged to the housings and hangs down over the openings thereof, as shown in Figure 1. These covers, of course, may be made more or less ornamental so that the devices will not take away from the attractiveness of the bed. I do not wish to be limited to the use of the pulleys.

90 The springs 23 are connected by the cords 24 to handles 29 which are disposed within the housings 30, extending from the elements 16 of the head board, the cord 24 passing upward through the curved portion 18 of the pipe 16 and then passing upward to the opening 26 of the pipe and then out through said opening. The housings 27 and 30 are designed to hold and partially enclose the foot pieces 28 and the handles 29 when the latter are contracted within the housings. These housings may be held in place upon the elements 16 by means of the metallic strips 31 or similar devices of this character. The longitudinal pipes or tubular elements 19 may be connected with the vertical elements 16 by means of unions 32 or like means.

In the use of this device, it will be obvious that the user lies upon his back on the bed or may take any other position desired and then by attaching the sandals 28 to his feet the legs may be exercised by flexing them against the action of the springs 22, and that by taking hold of the handles 29 the arms may be exercised by expanding the springs 23 and that a large number of different exercises may thus be had while lying in bed. It is obvious also that the body may flex against the action of the springs 22 and 23 and thus secure additional exercises.

While I have illustrated a particular form of bed and a particular design therefor, it is obvious that the principle of this invention might be applied to many different forms of beds and might be used either in a bed-like frame designed purely for the purpose of exercises or be applied to a regular bed. It also might be used for hospital beds.

It will be noted that all of the exercising apparatus is concealed within the bed frame so it is entirely hidden and even the sandal 28 and the handle 29 are normally enclosed within housings having decorative doors or panels whereby the handles and sandals may be entirely concealed so that the bed has the appearance of an ordinary bed and may be used as such. The exercising mechanism, it will be seen, does not in any way affect the use of this bed as an ordinary bed.

I claim:—

1. An exercising bed of the character described including in its construction vertically disposed rail members at opposite ends of the bed, longitudinally disposed hollow members connected to said vertical members, tension springs disposed within the horizontal members, a flexible connection connected to one end of each spring and extending longitudinally through the horizontal members and upward through corresponding vertical members and then out of the vertical member, the opposite end of the spring being held from movement, and body-engaging devices mounted at the outer ends of the flexible connections whereby said springs may be flexed by a flexing of the body.

2. An exercising bed of the character described having a foot element and a head element and including a pair of tubular hollow members and longitudinal tubular members, the vertical members having openings facing toward each other, contractile springs disposed in the horizontal members, a flexible connection extending from the outer end of each spring along the horizontal members and upward through the corresponding vertical members and out through the opening thereof, means at the extremity of the flexible connection whereby to connect it to the body of a person, and means for laterally

engaging the inner ends of said springs with the horizontal members to hold the inner ends of the springs.

3. An exercising bed of the character described comprising a foot board and a head board including hollow, vertical members, contractile springs connected to the body of the bed and each held at one end from movement, a flexible connection passing from the other end of each spring and passing through a vertical member and out through an opening therein, and body-engaging means on the end of each flexible connection.

4. A bed of the character described comprising a foot board and a head board, each having vertical tubular members, each tubular member having an opening, the lower ends of each of the tubular vertical members extending downward below the bed bottom and being bent parallel to the bed bottom, longitudinal hollow tubular members connecting the lower ends of the vertical tubular members, each longitudinal member having a plug disposed midway of its length, a pair of contractile springs disposed within each horizontal member, the inner ends of said springs being connected to the plug, flexible connections extending from the outer ends of the springs through the horizontal members and into the vertical members, up therethrough and out through said openings, and body-engaging means connected to the outer ends of said flexible connections.

5. A bed of the character described comprising a foot board and a head board, each having vertical tubular members, each tubular member having an opening, the lower ends of each of the tubular vertical members extending downward below the bed bottom and being bent parallel to the bed bottom, longitudinal hollow tubular members connecting the lower ends of the vertical tubular members, each longitudinal member having a plug disposed midway of its length, a pair of contractile springs disposed within each horizontal member, the inner ends of said springs being connected to the plug, flexible connections extending from the outer ends of the springs through the horizontal members and into the vertical members, up therethrough and out through said openings, and body-engaging means connected to the outer ends of said flexible connections, each of said vertical members at the opening having housings for enclosing the body-engaging members.

6. An exercising bed of the character described including a mattress-supporting frame having longitudinally extending hollow members and vertical hollow members, springs disposed within the longitudinally extending hollow members and each operatively connected at one end to the corresponding longitudinally extending member, a flexible connection attached to the other

end of each spring and extending out through an opening in a vertical, hollow member, and body-engaging means on the end of each connection.

5 7. An exercising bed of the character described including longitudinally extending members and hollow vertical members disposed at the ends of the longitudinally extending members and forming part of the

10 head and foot boards of the bed, contractile

springs connected to the bed and each held at one end from movement, a flexible connection passing from the other end of each spring and extending upward through a vertical member and passing out through an 15 opening therein, and body-engaging means on the end of each flexible connection.

In testimony whereof I hereunto affix my signature.

ROBERT HAYES GORE.
